(57) **CLAIM**

We claim the ornamental design for a foldable mobile phone with transitional graphical user interface, as shown and described.

DESCRIPTION

FIG. 1 is a front view of the first image in a sequence of a first embodiment of a foldable mobile phone with transitional graphical user interface showing our new design, with the transitional graphical user interface displayed on an outer display screen of the mobile phone in a folded state; FIG. 2 is a rear view thereof;

FIG. 3 is a front view of the second image thereof, with the transitional graphical user interface displayed on an outer display screen of the mobile phone in a folded state; FIG. 4 is a rear view thereof;

FIG. 5 is a front view of the third image thereof, with the transitional graphical user interface displayed on an inner display screen of the mobile phone in an open state; FIG. 6 is a rear view thereof;

FIG. 7 is a front view of the first image in a sequence of a second embodiment of a foldable mobile phone with transitional graphical user interface showing our new design

(Continued)

with the transitional graphical user interface displayed on an outer display screen of the mobile phone in a folded state; FIG. 8 is a rear view thereof;
 FIG. 9 is a front view of the second image thereof, with the transitional graphical user interface displayed on an outer display screen of the mobile phone in a folded state; FIG. 10 is a rear view thereof;
 FIG. 11 is a front view of the third image thereof, with the transitional graphical user interface displayed on an inner display screen of the mobile phone in an open state; FIG. 12 is a rear view thereof;
 FIG. 13 is a front view of the first image in a sequence of a third embodiment of a foldable mobile phone with transitional graphical user interface showing our new design with the transitional graphical user interface displayed on an outer display screen of the mobile phone in a folded state; FIG. 14 is a rear view thereof;
 FIG. 15 is a front view of the second image thereof, with the transitional graphical user interface displayed on an outer display screen of the mobile phone in a folded state; FIG. 16 is a rear view thereof;
 FIG. 17 is a front view of the third image thereof, with the transitional graphical user interface displayed on an inner display screen of the mobile phone in an open state; FIG. 18 is a rear view thereof;
 FIG. 19 is a front view of the first image in a sequence of a fourth embodiment of a foldable mobile phone with transitional graphical user interface showing our new design with the transitional graphical user interface displayed on an outer display screen of the mobile phone in a folded state; FIG. 20 is a rear view thereof;
 FIG. 21 is a front view of the second image thereof, with the transitional graphical user interface displayed on an outer display screen of the mobile phone in a folded state; FIG. 22 is a rear view thereof;
 FIG. 23 is a front view of the third image thereof, with the transitional graphical user interface displayed on an inner display screen of the mobile phone in an open state; FIG. 24 is a rear view thereof;
 FIG. 25 is a front view of the first image in a sequence of a fifth embodiment of a foldable mobile phone with transitional graphical user interface showing our new design with the transitional graphical user interface displayed on an outer display screen of the mobile phone in a folded state; FIG. 26 is a rear view thereof;
 FIG. 27 is a front view of the second image thereof, with the transitional graphical user interface displayed on an outer display screen of the mobile phone in a folded state; FIG. 28 is a rear view thereof;

FIG. 29 is a front view of the third image thereof, with the transitional graphical user interface displayed on an inner display screen of the mobile phone in an open state; and, FIG. 30 is a rear view thereof.
 The broken lines in the figures depict portions of the foldable mobile phone with transitional graphical user interface that form no part of the claimed design.
 The appearance of the transitional graphical user interface sequentially transitions between the images shown in FIGS. 1, 3 and 5; FIGS. 7, 9 and 11; FIGS. 13, 15 and 17; FIGS. 19, 21 and 23; and FIGS. 25, 27 and 29, respectively. The process or period in which one image transitions to another forms no part of the claimed design.
